(57) **CLAIM**

The ornamental design for a drinking vessel lid, as shown and described.

DESCRIPTION

FIG. 1 is a side view of a drinking vessel lid showing the new design;

FIG. 2 is a top perspective view thereof;

FIG. 3 is an exploded top perspective view thereof;

FIG. 4 is a bottom perspective view thereof;

FIG. 5 is an exploded bottom perspective view of the right side thereof;

FIG. 6 is an exploded bottom perspective view of the left side thereof;

FIG. 7 is a bottom view thereof;

FIG. 8 is a top view thereof;

FIG. 9 is a cross-sectional view along the line 9-9 of FIG. 8;

FIG. 10 is another top view, orientated counter clockwise 45 degrees in relation to FIG. 8; and,

FIG. 11 is a cross-sectional view along the line 11-11 of FIG. 10.

The shade lines shown at the top of the lid are provided to show contour and not surface ornamentation.
